UNITED STATES PATENT OFFICE.

SAM EVERETT FINLEY, OF ATLANTA, GEORGIA.

ROTARY SPRAY-NOZZLE FOR ROAD-TREATING MACHINES.

1,161,205.

Specification of Letters Patent.

Patented Nov. 23, 1915.

Application filed October 5, 1914., Serial No. 865,114.

To all whom it may concern:

Be it known that I, SAM E. FINLEY, a citizen of the United States, residing in the city of Atlanta, county of Fulton, and State 5 of Georgia, have invented certain new and useful Improvements in Rotary Spray-Nozzles for Road-Treating Machines; and I do hereby declare the following to be a full, clear, and exact description of the invention, 10 such as will enable others skilled in the art to which it appertains to make and use the same.

This invention relates to spray nozzles, and particularly to those intended for use on 15 machines for applying preservatives to roadways. Such a machine is disclosed in my co-pending application, filed April 5, 1913, Serial No. 759,044, and involves the use of spray nozzles adapted to deliver rotary 20 conical jets of the preservative to the road surface.

The object of the present invention is to provide such a spray nozzle having the improvements hereinafter set forth, and which 25 is particularly adapted for a machine of the type shown in the co-pending application above referred to. As will hereinafter be seen, however, the improved nozzle is not limited in its use to any particular type of 30 machine, and may be used in other relations than that shown, without departing from the scope of the invention.

The invention is illustrated in the accompanying drawing, in which:—

35 Figure 1 represents, in side elevation, the rear portion of a road treating machine, such as that disclosed in the co-pending application above referred to, with the improved spray nozzle applied thereto; Fig. 2 is a rear elevation of the improved nozzle; Fig. 3 is a vertical section, taken on the line 3—3, of Fig. 2; and Fig. 4 is a transverse section taken on the line 4—4 of Fig. 3.

40 Of the machine shown in Fig. 1, it is only necessary to note, for the present purpose, the pump A for delivering the preservative to the surface of the roadway through suitable piping comprising a header B disposed transversely of the roadway and provided 45 with a plurality of depending pipe sections C, to the lower extremities of which the spray nozzles are connected. By this means, the spray nozzles are disposed in a series arranged transversely of the road bed and are 50 properly spaced, so that the entire surface of the road bed will be treated. One of

such spray nozzles, forming the subject of the present application, is represented at D, and in its preferred form, is constructed as follows:

A main body portion 1 is provided, preferably consisting of a metal casting having an interiorly threaded inlet 2 adapted to be connected to the lower extremity of one of the depending pipe sections C. A circular outlet portion 3 is also formed on the main body portion 1 and is exteriorly threaded as shown at 4, to adjustably support a depending bracket 5. In the present instance this bracket consists of a split annular ring 6 having interior threads coöperating with the threads 4 of the outlet portion 3. A bolt and nut 7 serves as means for clamping the split ring 6 in its adjusted position with respect to the outlet portion 3. The split ring 75 6 carries depending arms 8, preferably formed integral with the ring 6, which arms carry a bearing portion 9 having a central longitudinal bore or opening adapted to receive the stem or bearing 13 of the conical distributor 10. A set screw 11 and lock nut 12 are carried by the bearing portion 9, so that the raising or lowering of the set screw 11 acts upon the bearing 13 of the conical distributor 10 to change the vertical adjustment 80 of the distributor in an obvious manner. If desired, an anti-friction ball 13' may be interposed between the set screw 11 and the extremity of the bearing 13, as shown in Fig. 3.

90 The conical distributor 10 coöperates with an outlet opening 14 formed in an annular ring 15, screwed into the interior of the outlet portion 3 of the nozzle.

The fluid in passing through the nozzle, 95 before reaching the opening 14, acts upon the radially disposed blades of a rotary member 16. The radially disposed blades are shown at 17, and may be sufficient in number to cause the member 16 to properly 100 rotate. The rotary member 16 is located in a vertically disposed portion 18 of the main body 1, to which vertically disposed portion, the fluid is admitted by means of a tangential passage 19, (Fig. 4). The fluid, in passing from the tangential passage 19, acts upon the radially disposed blades 17 of the rotary member 16, in such a manner as to rapidly rotate the same. The rotary member 16 is carried by a vertical pintle, the 105 lower end of which is threaded, as shown at 20, and screwed into the apex of the conical

distributer 10. The upper extremity 21 of the pintle is journaled in a bushing 22, preferably externally threaded and screwed into the upper part of the main body portion 1. 5 The bushing 22 is preferably carried as an integral part of a dome-shaped member 23, which is made hollow and serves to maintain a uniform pressure on the fluid in much the same manner as the dome on a pressure 10 pump. This is permitted by the fact that a portion of the fluid is allowed to pass between the pintle 21 and the bushing 22 into the opening of the dome-shaped member 23. From the foregoing construction, it will 15 be noted that the fluid admitted at the inlet 2 passes through the tangential passage 19 and acts upon the radially disposed blades 17 to rotate the rotary member 16. The member 16 being connected to the conical 20 distributer 10 causes the latter to rotate and to distribute the fluid directed thereon by the opening 14. The fluid is, therefore, delivered to the roadway in a conical jet, which has imparted thereto, a whirling motion, due 25 to the rotation of the distributer 10. It is preferable, though not necessary, to provide the distributer 10 with corrugations 24 to aid in the rotation of the distributer and also to comminute and break up the fluid into 30 small globules. The fluid, in expanding from a jet equal in size to the diameter of the opening 14 to a jet equal in size to the diameter of the spray, where it contacts with the road surface, causes the lighter constituents 35 of the preservative to volatilize, leaving only the heavier constituents, which are the most desirable for road treating purposes. The breaking up of the spray into globules, by means of the corrugations, aids in this volatilization of the lighter constituents in an 40 obvious manner. As a plurality of nozzles of the kind described are provided, arranged in a series transversely of the roadway, it is obvious that, as the machine is moved over 45 the roadway, all portions of its surface will be treated by the preservative from every angle. The improved nozzle is, therefore, particularly well adapted for machines for treating all kinds of paved roadways and 50 city streets, whether of concrete, macadam, bituminous concrete, or the like. It is adapted for surface treatment of hard roadways, as well as for coating broken stone with bitumen to form a bituminous macadam. 55 The several parts of the nozzle are capable of adjustment to suit various conditions, the bracket 5, for instance, being adjustable on the outlet portion 3 to bring the conical distributer 10 into proper relation with the 60 discharge opening 14. The position of the conical distributer 10 may also be changed by means of the adjusting screw 11. The quantity of preservative, or other fluid, applied to the treated surface depends upon the 65 size of the opening 14, and also the relative

position of the conical distributer 10 with respect to said opening, as obviously, if the conical distributer 10 is in close proximity to the opening 14, less fluid will be applied to the surface than if the conical distributer 10 70 were so adjusted as to be farther from the opening 14. The ring 15 may be readily removed and replaced by another ring having a different size opening therein when circumstances call for such a change. The 75 conical distributer 10 may also be replaced by a distributer of a different size or different shape. The improved nozzle is, therefore, capable of meeting a large range of 80 conditions.

As the rotary element 16 is continually rotated by the fluid, there is little danger of the nozzle becoming clogged. Furthermore, as a larger outlet opening can be used than in previous devices of this kind, clogging is 85 not as apt to occur as in former devices.

The nozzle above described is especially designed for delivering to the roadway, preservatives of low specific gravity. In fact, it has been demonstrated in practice that the 90 nozzle will successfully apply asphalt oils and tar products, running as high as 95% of bitumen, in quantities of $\frac{1}{4}$ of a gallon to one gallon to the surface square yard. No matter how heavy the preservative is, the rotary 95 member 16 will aid in preventing clogging of the nozzle, the relatively large outlet opening will permit a free flow of the fluid, and the rotary conical distributer will break up the stream of fluid directed thereon by 100 the opening 14 and properly distribute it to the road surface, the corrugations serving to break up the fluid into globules, as above described, and the expansion of the fluid serving to volatilize the lighter constituents, 105 as hereinbefore stated.

What I claim is:—

1. A spray nozzle for distributing fluids, comprising a body portion having an inlet and an outlet, a conical distributer adapted 110 to distribute the fluid issuing from the outlet, and a rotary element disposed in said body portion, said body portion having a passage tangentially arranged with respect to the rotary element to permit the fluid 115 to actuate the same.

2. A spray nozzle for distributing fluids, comprising a body portion having an inlet and an outlet, a conical distributer adapted 120 to distribute the fluid issuing from the outlet, and a rotary element disposed in said body portion and connected with said distributer, said body portion having a passage tangentially arranged with respect to the rotary element to permit the fluid to actuate 125 the same and the conical distributer.

3. A spray nozzle for distributing fluids, comprising a casing having an inlet and an outlet, a conical distributer adjacent said outlet and adapted to distribute the fluid 130

issuing therefrom, said distributor provided with corrugations, and a rotary element disposed in said casing and adapted to be actuated by the fluid passing through 5 the nozzle, and connections between said rotary element and said distributor whereby the former rotates the latter.

4. A spray nozzle for distributing fluids, comprising a body portion having an inlet 10 and an outlet, a conical distributor adapted to distribute the fluid issuing from the outlet, and a rotary element disposed in said body portion between said inlet and outlet and provided with radially directed wings, 15 the body portion having a passage to direct the fluid tangentially against said wings to rotate said element.

5. A spray nozzle for distributing fluids, comprising a casing having an inlet and an 20 outlet, a conical distributor adjacent said outlet and adapted to distribute the fluid issuing therefrom, and a rotary element disposed in said casing between said inlet and outlet adapted to be rotated by the fluid 25 passing through the nozzle, and means to adjust the position of the distributor with respect to the outlet.

6. A spray nozzle for distributing fluids, comprising a casing having a horizontally 30 disposed portion and a vertically disposed portion, the horizontal portion having an inlet and the vertical portion having an outlet, a rotary element disposed inside of the 35 vertical portion of the casing, the horizontal portion having a passage adapted to direct the fluid against the rotary element to rotate the same, a bracket carried by the vertical portion, and a conical distributor carried by said bracket to distribute the fluid 40 issuing from said outlet.

7. A spray nozzle for distributing fluids,

Copies of this patent may be obtained for five cents each, by addressing the "Commissioner of Patents, Washington, D. C."

comprising a casing having a horizontally disposed portion and a vertically disposed portion, the horizontal portion having an inlet and the vertical portion having an 45 outlet, a rotary element disposed inside of the vertical portion of the casing, the horizontal portion having a passage adapted to direct the fluid against the rotary element to rotate the same, a bracket adjustably carried by the vertical portion, and a conical distributor adjustably carried by said bracket to distribute the fluid issuing from 50 said outlet.

8. A spray nozzle for distributing fluids, 55 comprising a casing having a horizontally disposed portion and a vertically disposed portion, the horizontal portion having an inlet and the vertical portion having an outlet, a rotary element disposed inside of the 60 vertical portion of the casing, the horizontal portion having a passage adapted to direct the fluid against the rotary element to rotate the same, a bracket adjustably carried by the vertical portion, and a rotary 65 conical distributor adjustably carried by said bracket and connected to said rotary element to distribute the fluid issuing from said outlet.

9. A spray nozzle for distributing fluids, 70 comprising a casing having an inlet and an outlet, a corrugated distributor outside of the casing and disposed adjacent the outlet, and means in the casing actuated by the fluid passing therethrough to rotate said 75 distributor.

In testimony whereof I affix my signature, in presence of two witnesses.

SAM EVERETT FINLEY.
